UNITED STATES PATENT OFFICE.

FRANK R. ELBERT, OF FOSTORIA, OHIO.

CLASP.

No. 836,641.

Specification of Letters Patent.

Patented Nov. 20, 1906.

Application filed November 10, 1904. Serial No. 232,240.

To all whom it may concern:

Be it known that I, FRANK R. ELBERT, a citizen of the United States, residing at Fostoria, in the county of Seneca and State of Ohio, have invented new and useful Improvements in Clasps, of which the following is a specification.

My invention has relation to improvements in clasps for use in securing clothing, stockings, and other articles in position; and it consists in the construction and arrangement of parts, as will be hereinafter described, and particularly pointed out in the claim.

In the accompanying drawings, Figure 1 is a side elevation of the improved clasp. Fig. 2 is a central longitudinal section taken on the line 3 3 of Fig. 3. Fig. 3 is a side elevation of the clasp as viewed in a direction opposite to that of Fig. 1.

Referring to the drawings, 1 designates the clasp composed, preferably, from a single piece or blank of spring sheet metal folded adjacent its longitudinal center to produce a central transversely-disposed loop or eye 2 and a pair of opposed gripping-jaws 3 and 4, one of which terminates at its outer end in an inturned engaging portion or flange 5 and the other in a recessed engaging portion 6, having a groove or seat 7 for the reception of the flange 5, attention being directed to the fact that the clamping members or jaws 3 4 normally diverge outwardly from the eye 2 and are slotted longitudinally, as at 8, and, further, the jaws receive their spring action by means of said eye. Disposed within the slots 8 and extending between the jaws is an adjustable bolt 9, having at one end a head 10, provided with a washer 10' therewith, designed to bear upon the outer face of one of the jaws 40 and on opposite sides of one of the slots, and

a thumb-screw 11, applied on the other end of the bolt, having a washer 11' therewith, serves to bear upon the outer face of the other jaw and also on the opposite sides of the other slot, said washers serving to adjust the bolt, 45 and said washers and thumb-nut also permitting the jaws to be brought together and held in an adjustable position. In the eye 2 there is arranged an attaching member or clip 12, formed, preferably, from a single 50 length of wire bent into shape and having a strap-receiving opening or loop 13 for the reception of a suitable means 14 and an eye 15 for the reception of an analogous attaching device. 55

To operate the clasp, the jaws 3 and 4 may be opened to the appropriate extent for the reception of the article by moving the adjusting member 9 longitudinally of the slots 8, and after such adjustment the member 9, may be caused, by manipulating the thumb-nut 11, to tightly clasp and securely hold the article. 60

Having thus described the invention, what is claimed as new is— 65

A clasp comprising a strip of spring metal bent at its central portion to form a loop with a pair of clamping-jaws arranged to diverge relatively therefrom, said jaws having opposite longitudinal slots, a screw-threaded bolt 70 with a head thereon, said bolt being adjustably mounted in the slots and a thumb-nut on the bolt serving to force the jaws toward each other, substantially as specified.

In testimony whereof I affix my signature 75 in presence of two witnesses.

FRANK R. ELBERT.
